UNITED STATES PATENT OFFICE

JOHN FRANCIS ADAMS AND THOMAS T. ALLEN, OF PHILADELPHIA, PENNSYLVANIA,
ASSIGNORS TO SENTRY SAFETY CONTROL CORPORATION, OF PHILADELPHIA, PENN-
SYLVANIA, A CORPORATION OF DELAWARE

SAFETY DEVICE FOR MOTION PICTURE PROJECTING MACHINES

Application filed October 31, 1927. Serial No. 230,062.

Our invention relates to automatic control apparatus for motion picture projecting machines and more particularly to a safety device adapted to form the main unit of such apparatus.

One of the most prolific sources of fire in motion picture theaters is the ignition of the film, which is caused by its failure to move with sufficient rapidity through the rays of light from the lamp or by breaking and coming in contact with the lamp housing. If the film fails to move through the projecting machine at or above a certain rate of speed, the images are not projected upon the screen with sufficient rapidity to produce the illusion of continuous movement and oftentimes a decided flicker in the picture results.

One object of our invention is to provide a safety device adapted to intercept the rays of light passing through the film and stop the projecting mechanism whenever any incident or accident occurs which would tend to faulty projection or produce a fire hazard.

Another object of our invention is to provide a device which is compactly built and so simple in construction that there is little likelihood of its getting out of order.

Still another object of our invention is to provide a device of this character having few parts and which may be economically manufactured and installed.

According to the invention, the safety device comprises a casing having a shaft upon which a dowser is fixedly mounted, means on the shaft cooperating with tripping means for holding the dowser out of light obstructing position, an electromagnet and an armature for said magnet hingedly mounted thereon and adapted to be drawn to the electric magnet when it is energized, and means normally urging said armature away from said magnet and which, when the magnet is deenergized, will operate the tripping means to release the dowser and permit it to fall into light obstructing position. The casing is also provided with a switch which is located in the motor circuit and the shaft is provided with means which will open this switch when the dowser falls.

The drawings illustrate an embodiment

of the invention and the views therein are as follows:

Figure 1 is a rear elevation of a safety device embodying our invention; the rear cover of the casing being omitted and certain parts broken away.

Figure 2 is a side view looking from the right of Figure 1 but showing the casing cover in place; the casing and cover being shown in section and the other parts in full and certain parts broken away.

Figure 3 is a view looking from the left of Figure 1 but showing the casing cover in place and the greater part of the casing broken open to its center line.

Figure 4 is a detail plan view of a magnet armature, and

Figure 5 a wiring diagram showing the relation of our improved safety device to other elements forming an automatic control apparatus.

Referring now more in detail to the drawings, the device is shown as being provided with a casing 10 having a base 11 adapted to be secured upon the cone 12 of a motion picture projecting machine and adapted to fit various sizes of cones by means of fillers 13 disposed between base 11 and cone 12. The rear side of casing 10 is closed by a cover 14 preferably provided with an insulating lining 15. A shaft 16 is journaled in the front of casing 10 and in cover 14 and has a dowser fixed on its outer end which consists of a dowser handle 17 and a dowser plate 18.

A latch 19, rockably mounted in the bifurcated end of dowser handle 17, is adapted to be held between a stop 20 and a shoulder 21 when dowser plate 18 is positioned over the opening of cone 12. When dowser plate 18 falls, latch 19 will ride up the sloping face of shoulder 21, strike stop 20 and be drawn downwardly therebetween by a spring 22 having one end secured to latch 19 and its other end secured to dowser handle 17, thus preventing dowser plate 18 from oscillating and rigidly locking it in light obstructing position. To remove dowser plate 18 from light obstructing position, the operator depresses the hand grip 23 of latch 19, so as

to raise the end of latch 19 above shoulder 21, and swings dowser plate upwardly until dowser handle 17 strikes a stop 24 secured in the front wall of casing 10.

5 A trigger 26 is rockably mounted in casing 10 in any suitable manner, as by means of a screw 27 passing through trigger 26 and threaded into the front wall of casing 10, and extends through a suitable opening in 10 the side wall of casing 10 so that it may be manually operated. A collar 28 is fixed or formed on shaft 16 and provided with a notch 29 adapted to be engaged by trigger 26 for holding dowser plate 18 out of light 15 obstructing position. This may be accomplished in a number of ways but a suitable arrangement consists of securing a pin or stud 30 in the inner end of trigger 26 and rotatably mounting a roller 31 thereon which 20 is adapted to engage notch 29. To release the dowser, the outer end of trigger 26 is raised until roller 31 leaves notch 29, allowing collar 28 and shaft 16 to rotate and dowser plate 18 to fall. When raising 25 dowser plate 18 after trigger 26 has been released, roller 31 will ride on the periphery of collar 28 until it can enter notch 29 and hold the dowser in raised position.

30 A non-conducting switch base 32, secured in the bottom portion of casing 10, carries a spring contact 33 on one of its ends and a fixed contact 34 on its other end; suitable contact points 35 being preferably fixed to the meeting ends of the contacts. A cam 36, preferably made of insulating material, is fixed on shaft 16 immediately above spring contact 33 and is adapted to spring this contact away from fixed contact 34 when shaft 16 is rotated by the falling of dowser plate 18. An insulating bushing 37 is preferably disposed on shaft 16 between cam 36 and collar 28 and an insulating bushing 38 disposed between cam 36 and lining 15 of the casing cover. In order that there may be no possible chance of 45 short circuits or leakage of current between contact 33 and shaft 16, the joints between the ends of bushings 37 and 38 and the sides of cam 36 are filled with cement 39.

50 An electromagnet 41 has been shown secured in casing 10 by providing a cradle 42, having a flat face to abut the front wall of casing 10 and a concave face adapted to partially encircle magnet 41, and passing screws 43 through the casing and cradle and into 55 the shell of the magnet which, in the device illustrated, is made of metal.

56 A magnet armature 44 is adapted to rest on the top of the casing of magnet 41 and is provided with a slot 45 and an aperture 46. 60 An armature stop 47 is fixed to the side of the casing of magnet 41 and has an upwardly extending part of reduced width which passes through the slot 45 and is bent over armature 44. A hook 48 is formed on the lower end of armature stop 47 and supports the

lower end of a coil spring 49 whose upper end is secured to a bolt 50 which passes through aperture 46 and is held against downward movement by a nut 51. Magnet 41 is adapted to hold armature 44 against the upper end 70 of its shell against the action of spring 49 until it is deenergized when spring 49 will tilt armature 44 upwardly against stop 47.

Nut 51 is reduced in thickness for the greater part of its area so as to leave a projection 52 adapted to overhang the end of armature 44. To adjust its tension, spring 49 is stretched so that nut 51 may be moved in the desired direction on screw 50, the spring released and nut 51 turned so that 75 projection 52 overhangs the end of armature 44 and locks it against rotation; the tension of spring 49 should be such that it is capable of holding armature 44 against stop 47 when magnet 41 is deenergized.

80 A trip 54 has one end secured to armature 44 and a fork 55 secured to or formed near its other end and adapted to straddle trigger 26. The lower end of trip 54 is bent inwardly and supports a weight 56 which is adapted to add 85 impetus to the movement of the trip 54, when magnet 41 is deenergized and the armature swung upwardly by spring 49, so as to strike a blow against the under side of trigger 26.

85 The device is shown in Figure 1 in the position occupied when the projecting machine is in operation; magnet 41 being energized and its core slightly spaced from armature 44. When magnet 41 is deenergized, as will be hereinafter described, spring 49 swings 90 armature 44 upwardly and consequently swings fork 55 against trigger 26. Weight 56 being secured to trip 54, it will be swung upwardly by the action of spring 49 and the energy required to overcome its inertia positively assures the raising of trigger 26.

95 Referring now to Figure 5, we have shown the motor M, which drives the projecting machine, and the automatic control apparatus as deriving their power from a power line A-B through a switch 60 which has one of its holes connected to one side of motor M through a wire 61 and its other pole connected to one pole of a relay switch 62 by a wire 63; the other pole of relay 62 being 100 connected to the other side of motor M by a wire 64. One end of the winding 65 of relay 62 is connected to wire 63 and its other end is connected to contact 34 by a wire 66.

105 A centrifugal switch 67, which opens when the projecting mechanism has attained a certain speed, and film actuated switches 68 and 69, which are open when the projecting machine is in operation, are diagrammatically represented and shown as having one pole of each connected to wire 61 by a wire 70 and the other pole of each connected to one end of the winding of magnet 41 by a wire 71, thus putting these switches in parallel 110 with one another. The other end of the

winding of magnet 41 is connected to contact 34 by a wire 72 and contact 33 is connected to wire 70 by a wire 73. A resistance 74 has one side connected to wire 64 and its other side connected to wire 71 by a wire 75.

Assuming that switches 68 and 69 are open and the other switches closed, current may flow from switch 60 through wire 61, motor M, wire 64, relay 62, and wire 63, thus providing energy for the motor. At the same time, current may flow from wire 61 through wire 70, wire 73, contacts 33 and 34, wire 66, winding 65, to wire 63, thus energizing winding 65 and holding relay 62 closed. When the projecting mechanism has accelerated to projecting speed, switch 67 will open and current will also flow from contact 34, through wire 72, magnet 41, wire 71, wire 75 and resistance 74 to wire 64, thus energizing magnet 41 and holding trip 54 against actuating trigger 26.

If the film should break, tear or clog, or any other condition arise which would cause it to move substantially out of its normal path, one or both of switches 68 and 69 would be closed. If the film should slow down from any cause, such as unsufficient power to the motor or trouble in the motor or projecting mechanism, switch 67 would close. When one of these switches close, current may flow from wire 70 through the closed switch to wire 75 and thus momentarily deprive magnet 41 of a portion of its power and deenergize same sufficiently to allow spring 49 to swing armature 44 upwardly and cause trip 54 to raise trigger 26 and release the dowser. When the dowser falls, dowser plate 18 obstructs the light passing through the film and cam 36 separates contact points 35, thus breaking the circuit at this point and deenergizing winding 65 which would cause relay 62 to open and stop the motor.

A safety device made as above described is simple and inexpensive to manufacture, it possesses no parts which would ordinarily get out of order, and it is positive in operation.

Of course, the safety device illustrated may be modified in various ways without departing from the invention herein set forth and hereafter claimed.

We claim:—

1. A safety device for motion picture projecting machines including a dowser, means including a notched disc engaged by a trigger for holding the dowser out of light obstructing position, an electromagnet, an armature hinged on the magnet, a trip secured to the armature and adapted to strike the dowser-holding means to release the same, electrical contacts, means associated with the dowser for separating the contacts when the dowser falls.

2. In a device of the character described having a dowser held out of light obstruct-

ing position by a trigger, means for tripping the trigger including an electromagnet, an armature hinged on the magnet, a spring tending to tilt the armature, a trip secured to the armature and adapted to strike the trigger, and a weight secured to the free end of the trip to add impetus to the movement of the same.

3. In a device of the character described having a dowser held out of light obstructing position by a trigger, means for tripping the trigger including an electromagnet, an armature hinged on the magnet, a trip secured to the armature and adapted to engage the trigger, a spring secured to the magnet, and urging the same away from the magnet, a screw secured to the spring and extending through the armature, a nut on the screw, and a projection formed on the nut and overhanging the edge of the armature whereby the tension on the spring may be regulated and the nut prevented from accidental turning.

4. Safety mechanism for motion picture projecting machines comprising a shaft, a dowser on the shaft, means on the shaft cooperating with a trigger for holding the dowser out of light obstructing position, an electromagnet, and an armature for said magnet having a trip secured thereto, said armature normally held in engagement with the magnet by the energization thereof, but urged out of engagement therewith upon deenergization of said magnet, whereby the trip strikes the trigger and releases the dowser to permit it to fall into light obstructing position.

5. Safety mechanism for motion picture projecting machines comprising a shaft, a dowser on the shaft, means on the shaft cooperating with a trigger for holding the dowser out of light obstructing position, an electromagnet, an armature for said magnet having a trip secured thereto, said armature normally held in engagement with the magnet by the energization thereof but urged out of engagement therewith, upon deenergization of said magnet, whereby the trip strikes the trigger and releases the dowser to permit it to fall into light obstructing position, electrical contacts for closing the motor circuit, and means on the shaft adapted to open the electrical contacts when the dowser falls.

6. Safety mechanism for motion picture projecting machines comprising a shaft, a dowser on the shaft, a notched disc on the shaft cooperating with a trigger for holding the dowser out of light obstructing position, an electromagnet, an armature for said magnet hingedly connected therewith and having a trip thereon, and means urging said armature away from said magnet and which, upon the deenergization of said magnet, operates the trip to strike the trigger and thereby re-

lease the dowser to permit it to fall into light obstructing position.

7. Safety mechanism for motion picture projecting machines comprising a shaft, a dowser on the shaft, a notched disc on the shaft cooperating with a trigger for holding the dowser out of light obstructing position, an electromagnet, an armature for said magnet hingedly connected therewith and having a trip thereon, means urging said armature away from said magnet and which, upon the deenergization of said magnet, operates the trip to strike the trigger and thereby release the dowser to permit it to fall into light obstructing position, electrical contacts for closing the motor circuit, and means on the shaft adapted to open the electrical contacts when the dowser falls.
8. A safety device for motion picture projecting machines, including a dowser, means including a notched disc engaged by a trigger for holding the dowser out of light obstructing position, an electromagnet, an armature hinged on the magnet, spring means urging said armature away from said magnet, and a trip secured to the armature and adapted to strike the dowser holding means to release the same when the armature is pulled away from said magnet by said spring means.

In testimony whereof we have signed our names to this specification.

JOHN FRANCIS ADAMS.
THOMAS T. ALLEN.
